UNITED STATES PATENT OFFICE

OSCAR A. PEDERSEN, OF NEW YORK, N. Y.

CONCRETE BUILDING UNIT

Application filed March 11, 1927. Serial No. 174,496.

The present invention relates to improvements in building units and more particularly to improvements in building units comprising spaced slabs of concrete or similar building material separated by spacing and reinforcing members.

An object of the invention is to provide an article of this class in which the spacing and reinforcing means are in the form of steel beams and to provide in conjunction with the building unit means for insulating the slabs and for preventing passage of moisture and cold between the same.

The invention further aims to provide in conjunction with a building unit comprising spaced slabs of building material and steel beams for spacing and reinforcing the slabs, means for connecting and tying the reinforcing elements of the slabs to the steel beams whereby a stronger and more efficient construction is obtained.

With the above and further objects in view the invention further resides in the details of construction and arrangements of parts more particularly pointed out in the following description of the accompanying drawings forming a part of the specification.

In the drawings:

Figure 1 is a plan view of a portion of a steel beam adapted for application in the formation of the building unit of the present invention and showing the preferred means of attaching and tying the reinforcing elements of the slabs to the beam;

Figure 2 is a side elevational view of the beam disclosed in Figure 1;

Figure 3 is a sectional transverse view of the beam taken on the line 3—3 of Figure 2;

Figure 4 is a sectional transverse view through a building unit utilizing the beam disclosed in Figures 1, 2 and 3 and showing the manner in which the reinforcing elements of the slabs are attached to the beams;

Figure 5 is a plan view of a modified form of beam adapted for application in the formation of a building unit comprising the present invention;

Figure 6 is a bottom view of the modified form of beam;

Figure 7 is an end elevational view of the modified form of beam; and

Figure 8 is a transverse sectional view through a building unit utilizing the modified form of beam.

Referring now more particularly to the drawings in which I have shown by way of example several preferred embodiments of the present invention, in the modification shown in Figures 1 to 4 inclusive, I preferably employ as the spacing and reinforcing means for the slabs steel I-beams 10 and 11 which are placed one on top of the other in superposed relation and are spaced from one another by means of insulating material 12 which may be either wood, fibrous or any other insulating material. The beams 10 and 11 are clamped together as by means of rivets 13 and preferably around each rivet is placed a steel washer or bushing 14 to add strength and stability to the structure and to take up the stresses to which the beam is subjected in service. It will be understood that the bushings 14 are not an essential feature of the invention and that they may be omitted but their omission would cause a decrease in the strength of the building unit because of the fact that the insulating material 12 possesses relatively small strength and ability to withstand strain. Beneath the heads of the rivets, I preferably employ insulating washers, 15.

On the top and bottom of the members formed by the superposition and clamping together of the beams, 10 and 11, I preferably form prongs 16, the purpose of which will be apparent from a consideration of Figure 4. This figure shows the beam incorporated in a building unit and by reference to said figure it will be noted that the building unit comprises spaced slabs 17 and 18 of concrete or similar building material. In each slab there are incorporated reinforcing elements 19 and 20 which may be in the form of wire mesh, a metal lath, or any other variety. The reinforcing elements 19 and 20 of the slabs are engaged by the prongs 16 of the beams so that they are tied to the beams. Thus by my construction, I provide a building unit composed of spaced slabs of building material in which the spacing and reinforce-

ing means are in the form of steel beams and in which the steel beams interengage and interlock with the reinforcements in the slabs.

The insulation of the slabs 17 and 18 is not a perfect one as far as cold is concerned owing to the fact that there is some conductivity of cold through the steel beams. It will be appreciated, however, that the beams may be made perfectly nonconductive by completely insulating the members 10 from the members 11 but such insulation must be obtained at the sacrifice of strength and I have found it preferable to employ the construction described rather than to use a perfectly insulated construction.

It will be noted that between the beams 10 and 11 grooves 21 are formed and these grooves serve to accommodate and act as supporting means for boards or planks 22 of insulating material. I also preferably provide a web 23 of concrete or whatever other building material is being used. The webs, 23, may extend partly or wholly through the unit and serves to strengthen the same. It will also be noted that insulating members 12 and 22 are situated closer to the outside slabs 17 than to the inside slab 18. The purpose of placing the insulation close to the outside slab is to form a dead air pocket of such small width that the convection air currents do not have an opportunity to form and the conduction of moisture and cold by means of the convection air currents is thus practically eliminated. I thus provide a double means for insulating the building units, first by the use of insulating material and second by the presence of a dead air space between the slabs. In actual practise the space separating the outside slab from the insulation is made as small as one inch where the total thickness of the building unit is from eight to ten inches.

In Figures 5 to 8 I have disclosed a modified form of construction in which a special type of steel I-beam 30 is employed. The top 45 of this steel I-beam has upwardly extending side flanges 31 provided with prongs 32 adapted to be bent down into horizontal position as indicated in dotted lines in Figure 7. The bottom of the I-beams 33 are similar in 50 character to the prongs of the first modification described. The I-beam supports on its sides two small channel irons 34 which are welded or otherwise attached in position. When the beam is incorporated in the building unit as indicated in Figure 8, the channel irons serve to accommodate and support the insulating planks 35. In this modification of the invention the insulating planks are also placed closer to the outer slab 17 for 55 the same purpose as in the modification first described. The prongs on the bottom of the beam also engage the reinforcing elements 20 of the lower slab 18 for tying the lower slab and securing the same more firmly to the beam. On the top of the beam an insulating

member 36 is disposed and is clamped in place by bending down the left hand prongs 32. The right hand prongs 32 of the beam serve to engage and interlock with the reinforcing element 19 of the slab 17 and to tie the same to the beam. The provision of the insulating member 36 cuts down to a great extent the amount of cold capable of passing through the I-beam and provides a better insulation for the building unit.

By my invention I have provided a building unit utilizing steel beams which is very strong and sturdy in construction and amply capable of withstanding the forces and stresses to which it is subjected in service. I use a reinforcing and spacing means for the concrete slabs and at the same time provide means for tying the slabs to said means so that there is no danger of the slabs falling apart and the strength of the unit as an entity is increased to a great extent thereby. I have also provided with a steel reinforced building unit means for insulating the slabs which is extremely effective as far as moisture is concerned although it does leave a small conductive path through the steel beams for penetration of cold. However, this path has been restricted to such a small size that the amount of cold that can pass through is slight and this disadvantage is more than offset by the increase in strength in the building unit resulting from the employment of the steel spacing and reinforcing means.

While I have described specific embodiments of the invention it will be understood that modifications and variations may be made in the various details of construction without departing from the spirit of the invention and I desire to be limited only by the state of the prior art and the scope of the appended claims.

I claim:

1. A building unit comprising spaced slabs of building material, and means between the slabs and spaced therefrom for dividing the space between the same into a plurality of separated spaces of different sizes, at least one of said spaces being so small as to prevent the formation of convection air currents, said means comprising an insulating member positioned between the slabs in parallel relation therewith.

2. A building unit comprising spaced slabs of building material, reinforcing elements in the slabs, steel members for spacing and reinforcing the slabs, prongs on the steel members for engaging the reinforcing elements of the slabs, and insulating members adapted to be disposed between the slabs and supported in grooves on the steel members.

3. A building unit comprising spaced slabs of building material, steel beams embedded in the slabs and insulating members covering the ends of the beams and spacing said beams from the slabs.

4. A building unit comprising spaced slabs of building material, steel members embedded therein for spacing and reinforcing said slabs, insulating members disposed between said slabs, and means for supporting said insulating members in spaced parallel relation to said slabs.

5. A building unit comprising spaced slabs of building material, a steel member adapted to support said slabs and disposed between them, a reinforcing element embedded in the slabs, and projecting prongs on said steel element for engaging said reinforcing elements.

10 6. A building unit comprising spaced concrete slabs, steel I-beams arranged in superposition between the slabs for spacing and reinforcing the same, and insulating members clamped between adjacent beams.

20 7. A building unit comprising spaced concrete slabs, flanged steel beams between the slabs for spacing and reinforcing the same, said beams having flanges embedded in said slabs and a member extending transversely 25 of the beams intermediate the ends and flanges thereof.

8. A building unit comprising spaced slabs of cementitious material, metal members between the slabs for spacing and reinforcing the same, and cold insulating means separating said metal members for limiting the passage of cold therethrough.

9. A building unit comprising spaced slabs of cementitious material, metal members between the slabs for spacing and reinforcing the same, means separating said members for limiting the passage of cold through said metal members.

10. A building unit comprising spaced 40 slabs of cementitious material, metal members between the slabs for spacing and reinforcing the same, means for limiting the passage of cold through said metal members, and insulating members disposed in the space 45 between the slabs and supported by the metal members.

In testimony whereof, I have signed my name to this specification this 10th day of March, 1927.

50 OSCAR A. PEDERSEN.
